(57) **CLAIM**

We claim the ornamental design for a container for a game, as shown.

DESCRIPTION

FIG. 1 is a perspective view of a container for a game showing our design;

FIG. 2 is a left elevational side view of the design shown in FIG. 1;

FIG. 3 is a right elevational side view of the design shown in FIG. 1;

FIG. 4 is a front elevational view of the design shown in FIG. 1;

FIG. 5 is a rear elevational view of the design shown in FIG. 1;

FIG. 6 is a top plan view of the design shown in FIG. 1; and, FIG. 7 is a bottom plan view of the design shown in FIG. 1.
